(57)

CLAIM

The ornamental design for a desktop receptacle, as shown and described.

DESCRIPTION

FIG. 1 is a perspective view of a desktop receptacle showing my new design;

FIG. 2 is a front view thereof;

FIG. 3 is a rear view thereof;

FIG. 4 is a top view thereof; and,

FIG. 5 is a side view thereof.

In the drawings, the broken lines represent portions of the desktop receptacle that form no part of the claimed design.
